INVENTOR
Cecil W. Humphrey,
by
Arthur B. Jenkins,
ATTORNEY

UNITED STATES PATENT OFFICE.

CLAYTON W. HUMPHREY, OF UNIONVILLE, CONNECTICUT.

JOINTED RULE.

Application filed June 12, 1925. Serial No. 36,743.

My invention relates to the class of measuring devices that are adapted to be folded when not in use, and an object of my invention, among others, is the production of a rule having a joint that is simple in construction and possesses means for locating the blades in different angular positions, said joint at the same time being compact and amply strong to resist the forces to which it is commonly subjected in use.

One form of a rule embodying my invention and in the construction and use of which the objects herein set out, as well as others, may be attained, is illustrated in the accompanying drawings, in which—

Figure 1 is a face view of a rule comprising several blades connected by my improved joint, the several blades being folded into closed position.

Figure 2 is an edge view of the same.

Figure 3 is a detail sectional view, scale enlarged, through a portion of two blades and the pivot joint embodying my invention.

Figure 4 is a view similar to Figure 3 but of a single blade only showing one member of my improved joint.

Figure 5 is a face view of one end of a blade having one member of my improved joint secured thereto.

Figure 6 is a similar view, but showing the other member of the joint.

Figure 7 is a view in section on a plane denoted by the dotted line 7—7 of Figure 3.

Figure 8 is a view similar to Figure 4, but showing the other member of my improved joint.

While my invention is not especially limited in its application to any particular kind of a rule or similar device, yet as it is well adapted for use to connect the blades of what is commonly known as a "zigzag rule" I have selected such for the purpose of illustrating my invention in the drawings herein, in which the numerals 9—10 indicate two blades of a rule connected by a joint embodying my invention, a complete rule comprising several of said blades being shown in Figure 2, but the description herein being confined to two blades only as sufficient for a clear understanding of the invention, it being understood that all of the joints may or may not embody my invention.

A hole 15 is formed in the hub 13 concentric with but larger in diameter than a hole 16 extending through the blade 9. The other blade 10 has a hole of the same diam-

eter as the hole 16 and a pawl plate 17 is secured in a recess 18 in the end of the blade similar to that at the end of the blade 9, a pawl retaining recess 19 opening into said recess 18. In the specific form shown the plate 17 has a projection the edges of which are struck up to constitute a flange to hold the loop, this projection being retained in the recess in the blade and as shown in Figures 6, 7 and 8 of the drawings. This plate 17 has a retaining hub 20 of a diameter to fit the hole 16 in the plate 11, said hub being received in said hole so that the end of the hub may bear against the blade 9 at the bottom of the hole 15. A hole 21 is formed through the hub 20 of a size the same as the hole 16, said holes 16 and 21 being of the diameter of a stud 22 that extends through said holes and that may be headed to rotatably join the plates 9 and 10.

Pawl 23 are formed at the ends of spring arms 24, said arms preferably comprising a single piece of wire bent into a retaining loop 25 at their joined ends, said loop being formed to fit within the recess 19 to be held therein, and the pawls 23 at the ends of said arms being formed to fit within the notches 14 comprising ratchet teeth in the positioning hub 13.

It will be understood that the joint composed of the members, as hereinbefore described, is very compact and that the blades are located at a minimum distance apart. The blades may be rotated one with respect to another by the application of a little force and when positioned with the pawls engaging the teeth of the ratchet the blades will be frictionally held with sufficient rigidity for all of the purposes to which a rule of this character may be subjected.

In accordance with the provisions of the patent statutes I have described the principles of operation of my invention, together with the device which I now consider to represent the best embodiment thereof, but I desire to have it understood that the device shown is only illustrative and that the invention may be carried out by other means and applied to uses other than those above set out.

I claim—

1. A blade, a plate secured thereto, a hub projecting from said plate, another blade, a plate secured thereto and having a recess to receive said hub, a pawl attached to said

- first named plate, a ratchet attached to the last named plate and having teeth to be engaged by said pawl, and means for pivotally connecting said plates.
5. 2. A blade, a plate secured thereto and having a ratchet with ratchet teeth, a second blade, a plate secured thereto and having a recess, a pawl comprising branching arms with a loop at the joined portions of said 10 arms located within said recess, the ends of the arms comprising pawls to engage said ratchet and means for pivotally connecting said plates.
15. 3. A blade, a plate secured thereto and having a hub with ratchet teeth thereon and a hub receiving recess therein, a second blade, a plate secured thereto and having a retaining hub to engage the recess in the first mentioned hub, said last mentioned
- blade having a pawl receiving recess, a pawl 20 comprising a single piece of material bent into a loop located in said pawl receiving recess, said pawl comprising branches the ends of which are formed to engage said ratchet teeth and means for pivotally connecting said plates.
4. A blade, a plate secured thereto, a hub projecting from said plate and having an opening therethrough, a second blade, a plate secured thereto and having a hub with 30 an opening therethrough and a recess therein to receive the hub of the first mentioned plate, a pawl upon one of said plates, a ratchet on the other plate having teeth to be engaged by said pawl, and means for pivotally connecting said plates.

CLAYTON W. HUMPHREY.
